W. B. Parker

Attorney

UNITED STATES PATENT OFFICE.

MARTIN EVALD OLSON, OF MINNEAPOLIS, MINNESOTA.

BENCH CLAMP.

Application filed May 17, 1926. Serial No. 109,802.

This invention relates to work holding devices and the primary object is to provide a practical, efficient and comparatively simple and easily operated bench clamp, which has 5 a wide variety of uses but is especially adapted for use by carpenters, cabinet makers and other wood workers. Further and more specific objects will be disclosed in the course of the following specification, reference being had to the accompanying drawing, wherein:

Fig. 1 is a plan view of a bench equipped with my improved bench clamp.

Fig. 2 is a front elevation of the bench 15 and clamp as shown in Fig. 1.

Fig. 3 is a sectional elevation as on the line 3—3 in Fig. 2.

Fig. 4 is an enlarged sectional detail view 20 as on the line 4—4 in Fig. 1.

Referring to the drawing more particularly and by reference characters, A designates the top of any suitable bench or table having legs B. The clamp comprises two separate and independently secured units C and D, 25 which may be respectively described as follows:

The unit C consists of a casting 5 which is clamped upon the bench or table A, and against the front edge thereof, by a screw 6 30 having a handle 7. The casting is provided with a lug 8, the end face of which is preferably provided with a leather or fabric facing 9, adapted to abut the piece to be clamped and thus prevent marring of the work. This 35 may be considered as a secondary jaw, however, while the primary jaw comprises the corrugated or roughened end face 10 of a head 11 which has a shank 12 slidably carried in a vertical recess 13 in the lug 8. The 40 shank 12 is provided with a spring member 14 for frictional engagement against an inner wall of the recess 13, to hold the member 11—12 in any vertical position to which it may be adjusted. It may here be noted 45 that the shank 12 may be reversed in the lug 8 so that the smooth end of the head 11 may be substituted for the rough end 10, to prevent marring of the work, and that the member 11—12 may be entirely removed 50 when it is desired to use the fabric faced jaw 9 only. This is also true of the corresponding elements of the clamping unit D.

The unit D consists of a casting 16 which is secured to the bench by a clamp screw 17

having a handle 18. The casting 16 is provided with a horizontal longitudinal slot in which is reciprocally carried a slide bar 19 having a head 20 which is faced as at 21 and is directly opposed to and in clamping relation with respect to the faced boss or lug 8 of the unit C. The head 20 is provided with a vertical slot in which is carried a shank 22 having a retaining spring 23, and a head 24 having a roughened end 25 which contacts with the jaw face 10 of the head 11. 55

The right or inner end of the slide bar 19 is provided, in its back side, with a notch 26 which slidably receives the outer flange 27 of a cam 28 which is rotatably carried on a bolt 29 (rigid in the casting) and which has 70 an operating handle 30. The gripping action is obviously imparted by the cam to the slide bar by operating the handle 30, and the clamp is locked or set in its tightened position by a lock nut 31 which screws on 75 the bolt 29 and is manipulated by a handle 32. It may here be noted that the top or inner end of the flange 27 is provided with a notch 33, the object of which is to permit the bar 19 to be slid into operative engagement with the flange, and thus renders it possible to make the bar of one piece of material, while if it had to be passed over the flange it will be seen that the cam end would 80 no doubt have to be releasable or detachable 85 to effect the movement. A further object of the notch 33 is to permit a quick and easy removal of the members 19 and 22 to render the entire device inoperable and consequently useless. Such a contingency might arise 90 where a workman has taken the device to a job where he wishes to use it for several days, but does not desire to carry it back each evening to prevent it from being stolen. Instead of doing this he may merely remove 95 the bolt 19 and either conceal it or carry it with him until he returns. There will thus be no incentive for a thief to steal the inoperative and useless parts which remain 100 during the workman's absence.

The use and operation of the device may be briefly described as follows: The clamp unit D is first secured to the bench or similar support and near the right end of the same. The unit C is then placed upon the support 105 and is moved to the proper position, which position is determined by the size of the piece to be clamped, and is there securely fastened

by drawing up the bolt 6. The piece is then inserted and the lever 30 is pressed down until the proper or desired clamping pressure is exerted, at which time the handle 32 is turned to lock the cam 28 against reverse rotation.

It is understood that suitable modifications may be made in the general design and structural details of the invention as herein shown and described, provided, however, that said modifications come within the spirit and scope of the appended claim.

Having now therefore fully shown and described my invention, what I claim to be

new and desire to protect by Letters Patent is:

A bench clamp comprising a pair of opposed units one of which is provided with a normally stationary clamp member, a horizontally movable bar carried by the other unit and having a complementing clamp member, a cam member having a flange for engagement with and to actuate the bar, said flange having a notch which when registered with the bar will permit the removal of the same from the unit.

In testimony whereof I affix my signature.

MARTIN EVALD OLSON.
